RACING APPARATUS

William C. Ford, Andover, Mass.

Application April 3, 1950, Serial No. 153,535

15 Claims. (Cl. 273—86)

1

This invention relates to amusement devices of the type in which a plurality of racing figures are caused to advance, in competition with each other, at continually changing rates of speed, the speed being controlled by chance.

I am aware that it has been proposed to advance such racing figures by placing them on moving belts, roller conveyors, revolving coil springs or vibrating or oscillating platforms. This method of advancement is what I call the direct method in that the figure advances because the race course advances. Of course with the race course and figure both moving in the same direction the illusion of racing is somewhat lessened and I therefore avoid this construction.

I am also aware that certain indirect methods of advancement have been proposed, to overcome the above disadvantage, such as providing a slotted race course which remains stationary while the racing figure is propelled along the guide slot by means of a periodic push received from a moving member underneath the race course. In such devices the racing figure usually is supported by forward and rear wheels resting on the race course and has a depending arm projecting through the guide slot and into the path of actuators on the moving member.

My device is of the type just described in that it has an upper member which is slotted and corresponds to a race course. In addition, each of my racing figures has a depending arm projecting through a guide slot and into the path of actuators carried by a lower member. My apparatus differs from other such indirectly actuated devices, however, in the novel features explained hereafter.

One of the objects of my invention is to provide a racing figure with the appearance of a galloping animal, the figure being so formed, and so mounted on the upper member of the amusement device, that it simulates galloping as it is actuated from below.

Another object of my invention is an amusement device having slots in the upper member to guide my new racing figures, and having a lower member provided with fixed actuators arranged to rock each figure as it advances the figures abreast of each other.

A further object of my invention is to provide an improved chance actuator on the lower member arranged to change its contact relation with each racing figure and thus to continually vary the rate of advancement of each figure.

A still further object of my invention is to provide an amusement device comprising racing

2

figures which appear to gallop as they advance, at chance determined rates of speed, along a slotted upper member, the upper member being either straight or circular and being either moving or stationary, as described.

By the term "fixed actuator," I mean a strip of material fixed across the path of the depending arms of my racing figures which rocks and slides said figures on their pivots a similar amount each time contact between them is made. By the term "chance actuator," I mean an actuator similarly located but having irregularities on its surface and being movable whereby each time contact is made, the figures are affected in unequal amounts.

The most advantageous embodiment of my invention simulates a race of four legged animals such as dogs or horses. I have discovered that racing figures having a depending arm extending below the figure and through a slot can be caused to rock from front to rear like a running four legged animal if pivoted, weighted and actuated as described herein.

The racing figures of my device are supported on a single transverse pin extending across a guide slot in the upper member so that the figure is what I call rockably mounted. This is in contradistinction to previous devices in which the figure may be a horse on wheels, or a racing car, so guided on a track that, instead of rocking, they progress smoothly when pushed from below.

The depending arm of my racing figure is not pivoted to the figure as in prior devices, which have been designed to allow the figure to advance in a horizontal position. Instead the depending arm is integral with my racing figure whereby when the depending arm is struck by actuating elements on the lower member, the figure slides along the guide slot as it rocks backward on its pivot and the figure then rocks forward to its original position.

The motion developed is not a smooth momentary drawing forward of the figure but rather an impulse momentarily counteracting the weight of the figure on the upper member and causing it to move to a slightly advanced position in the guide slot.

I have discovered that if the depending arm of a racing figure according to my invention is supported on the upper member in two places or, if supported on only one pivot and the centre of gravity is directly below the figure, the figure may advance, but not in the desired manner. If so constructed the figure tends to catch on the actuators to be knocked out of the slot and may

swing haphazardly and occasionally advance to the end of the slot without stopping at all.

To overcome this disadvantage I may use a figure having a depending arm of light material and so weighted in the nose of the figure, above and in front of the single transverse pivot pin, that the centre of gravity is at the front of the figure. When rocked backward the figure instantly returns to its normal position of rest on the actuator carrying member in this construction.

I prefer, however, to use a racing figure the integral depending arm of which is heavier than the figure above the slot and is curved forwardly toward the nose of the simulated animal thus placing the center of gravity not only below the pivot and the slot but in front of the pivot. The moment of force about the pivot is thus so arranged that each time the depending arm is lifted by an actuating member, the figure moves along the slot while it rocks back and rocks forward to its normal position.

I also prefer to construct my device so that the slotted upper member is fixed and the lower member which carries the actuating element moves beneath the upper member. The upper and lower members may be circular, in simulation of a curved track or they may be straight in simulation of a straightaway race.

However, I may construct my invention with a moving slotted upper member revolving above a lower member which is fixed, in the manner of a wheel of chance. In this embodiment I use the same type of rocking figure with a depending arm such as is used with the fixed track or race course, but the arm extends rearwardly opposite to the direction of travel of the upper member. The head of the racing figure may be faced in the direction of travel of the upper member or in the opposite direction, in either case preserving the illusion of a race between galloping figures.

With a moving upper member, each time a figure is carried past an actuator on the lower member, the weight of the figure is temporarily counterbalanced and the upper member goes out from under it a slight amount. Thus each figure progresses with relation to the upper member, upon each actuation, in the direction opposite to the direction of travel of the upper member. As illustrated in the drawings, this modification of my device is preferably circular although it is obvious that it could also be constructed as a straightaway course.

A particularly novel feature of my invention is the actuating elements which give my racing figures the illusion of continually galloping or running animals. In prior devices the actuators may consist of knots in a cable or upstanding lugs carried by a belt each arranged to engage a part of the racing figure, push it forward slightly and release it causing the figure to advance intermittently by a series of advances and halts.

My actuators are preferably evenly spaced on the lower member and extend completely across the same thus giving each figure an equal impulse as the actuators contact the depending arm of each figure. For example if there are six racing figures and eight transverse actuators spaced along ten inches of the lower member, each of the six figures will appear to make eight distinct gallops as their depending arms contact ten inches of the lower member.

In the circular construction of my device, where

the inside slots are proportionally shorter than the outside slots I may compensate by using actuators which are progressively higher as they approach the outer periphery, thus giving a correspondingly greater impulse to the outer racing figures. I may also compensate by increasing the friction between the pivot pin and upper member for the inner racing figures so that they encounter more frictional resistance than those figures in the outside slots. Of course, the outer figures travel at a greater speed than the inner figures and thus receive a greater lift from the actuator, this greater lift also serving to equalize the rate of travel of the figures.

15 The competition between figures, in other words, the racing or chance element of my device, consists in the novel revolving actuator which I intersperse among the fixed actuators on my lower member. I prefer to use one chance actuator with every six or seven fixed actuators because I have found that the human eye cannot detect the influence of such a proportion of chance actuators during the steady forward progression of my rocking, racing figures. However, it is 20 25 obvious that all my actuators could be of the chance type or any desired proportion of the same could be used to give various effects to the race.

My chance actuators may be of greater or less 30 height than the fixed actuators and may be constantly revolved by contact with the arm of each racing figure or by means of gears or friction wheels driven by the moving member. I provide permutations which may be in the form of 35 cut out sections in each chance actuator in the path of the depending arms of my racing figures so that as the actuator is revolved, certain racing figures will be rocked and moved more or less than the others. I prefer an occasionally 40 slipping friction drive for my chance actuator so that there is no danger of repetition of cycles as the moving member advances. However, a positive gear drive, in view of the positioning and 45 variety of shape and size of the cut out sections and friction between figure and race course gives an excellent result.

In operation my racing figures are started in a straight row in slots in the upper member and, as the lower member contacts them from below, the figures may advance neck and neck and galloping evenly for a short distance. Then as a chance actuator contacts them one or more figures will be rocked and slid a different amount and will lose ground or gain ground with relation to the remaining figures. The figures continue to gallop forward steadily however, each rocking on its pivot until another chance actuator makes contact. The failure of several more figures to rock and slide the same amount as other 50 55 60 figures will again change their relative positions and the race thus continues to a finish line.

I provide a pivoted sweeping arm to return the figures to their original position in my circular race course type and may use a sliding arm to return them in the straightaway type. I also provide an electric or spring driven motor, to give motion to the moving member of my device and may provide suitable speed changing mechanism therefor, all well known in the art.

65 The speed at which my moving member travels in relation to the fixed member is preferably just sufficient to make each racing figure slide along the upper member as it rocks without perceptibly losing contact with said upper member. If operated at high speed the figures might be jolted

out of the slot and if at too low a speed the figures might simply rock and not slide at all.

It is apparent that my device may be constructed on a large scale with full size racing figures capable of carrying an adult or child and with a circular or straight race course. In such case the shifting of the weight of each rider adds an additional element of chance to the race. I may provide a forward and a rear stop on each figure to limit the rocking motion and may also use a coil or leaf spring to smooth out the rocking motion in a large scale construction.

Fig. 1 is a side view in section of my device with the upper member a straight stationary race course.

Fig. 2 is a plan view of the device shown in Fig. 1.

Fig. 3 is a side view in section on line 3—3 of Fig. 4, showing my device with the upper member a circular stationary race course.

Fig. 4 is a plan view of the device shown in Fig. 3 on a smaller scale.

Fig. 5 is a plan view in section on line 5—5 of Fig. 3, on a still smaller scale.

Fig. 6 is an elevation in section on line 6—6 of Fig. 7 of my device with the upper member a circular race course which revolves.

Fig. 7 is a plan view on a smaller scale of the device of Fig. 6.

Fig. 8 is a view similar to Fig. 7 and showing one method of compensating so that each racing figure travels the same distance.

Fig. 9 is an enlarged elevation of the preferred form of my racing figure, showing in dotted lines the rocking and sliding motion caused by the actuators.

Fig. 10 is a similar view of a modified form of racing figure.

Fig. 11 is an enlarged cross section of my preferred form of chance actuator on line 11—11 of Fig. 13.

Fig. 12 is a similar view on line 12—12 of Fig. 14 of a modification of my chance actuator.

Fig. 13 is a side view of the device of Fig. 11.

Fig. 14 is a side view of the device of Fig. 12.

In Figs. 1 and 2, I show a form of my device in which the stationary upper member 1 is fixed to a casing A while the lower member 2 moves beneath it. A number of straight guide slots 3, 3 are provided in 1, commencing at the start 4 and ending at the finish line 5.

Racing figures F, simulating an animal with a nose N and a tail T, have an opening 11 in which a single horizontal pivot pin P is fixed. The pin P extends on each side of figure F and rests on the surface of upper member 1 so that the figure is enabled to rock backward and forward. Integral with F is a depending arm 12, extending through the slot at 13, of sufficient width to permit the slot 3 to guide the figure in a straight course. The arm 12 projects forwardly in a curve at 14 and is of such weight that the centre of gravity of the entire racing figure F is well below and ahead of the pivot pin P.

Lower member 2 comprises an endless belt 20, carried by pulleys 21 and 22 journaled in frame A and driven by an electric motor M through a drive belt 23. A spring driven motor or a suitably geared manually operated hand crank may also be used in place of M.

Fixed by any convenient means preferably at regular intervals along the exterior surface of belt 20 are what I call fixed actuators 24, 24, which extend transversely of the belt and may be of semi-circular cross section or other shape.

Fixed actuators 24 are so positioned under the guide slots 3 that as moving member 2 passes beneath the curved part 14 of a racing figure F, the actuator raises 14 and the figure rotates in a clockwise direction around pivot pin P. At the same time the weight of the entire figure F is substantially counteracted, causing pin P to slide along upper member 1 and to make a slight advance along the slot 3 before rotating back into place on pin P.

In place of one or more fixed actuators 24, at various points around moving member 2, I place what I call a chance actuator C to give the competitive or chance element to my device. As shown in Figs. 11 and 13, the chance actuator may comprise a cylinder 32 of rubber, wood or other suitable material carried on a shaft 33 journaled in bearings 34 supported on belt 20 of moving member 2. At the points on the surface of C, beneath each guide slot such as 3 where the depending arm 12 of figures F would normally be contacted, I provide cut out portions 35, 36, 37 and 38 staggered around the circumference in a variety of depths and circumferential locations. These cut out portions are the permutations of my device and cause each racing figure to react differently depending on whether its depending arm 12 is contacted by a full cut out, a partial cut out or by no cut out.

Since the chance actuator C is capable of revolving in its bearings 34, I may utilize the turning effect of the drag of each arm 12 of each racing figure F to revolve the cylinder and thereby move the cut outs to new locations. However, I prefer to attach a pulley 39 to the end of shaft 33, the surface of the wheel being in contact with the under part of 1 or the bottom of casing A or both and caused to revolve thereby. I also prefer that the rotation of pulley 39 be of a slipping, uncertain drive to give no possibility of the chance actuator C continually repeating the same cycle.

When the first racing figure F has reached the finish line 5 on top member 1, movement of the lower member 2 may be stopped by any well known stop means such as the contact arm of an electric switch, if desired, and a sweep arm 40, slideable in a slot 41 in casing A is provided to engage the figures and return them to the starting point 4 in slots 3.

Instead of the straight track shown in Figs. 1 and 2, I may provide a curved track G, also having a fixed or stationary upper member 50 and having a moving lower member 60. Member 50 has concentric slots 51, 51 with a starting point 52 and finish point 53 and a sweep arm 54 is pivoted at 55 for the purpose of returning the figures H, H to the starting point.

Moving member 60 is a horizontal disc pivoted at 61 and may be revolved by manual or power operated means such as a motor M. Fixed actuators 70 are positioned radially around moving member 60 and several chance actuators 71 are interpersed among them, revolved by pulleys 72 in the manner described above. As shown in Fig. 3, I may also compensate for the difference in length of slots 51, 51 by forming my actuators 70 so that they are of progressively greater height as they approach the outer periphery of the disc, thus giving a greater impulse to the outside racing figures.

In Fig. 6, I show a further modification of my invention in which the upper member 80 is a moving member and the lower member 90, which carries the actuators is stationary. Upper

member 80 may have slots 81, 81 of unequal length, as in Fig. 7, each slot having a starting point 82 and a finish point 83 on radial lines from the centre. The upper member 80 is pivoted for rotation above the centre of lower member 90 and is supported on a bearing 84 upon which it may be spun by the hand of the operator or it may be power driven by any suitable means as indicated in other forms of my invention.

Fixed actuators 91, 91 and chance actuators 92, 92, may be used to give impulses to racing figures J, J in the manner explained above. However, I may provide a circular toothed rack 85, concentric with 80, and attached to the underneath portion thereof to give a positive drive to spur or bevel gears 95 adapted to revolve chance actuators 92. In such cases I avoid a construction in which the circumference of gear 95 is a divisor of the circumference of gear rack 85 thus assuring that the element of chance is practically infinite. It is obvious that I can also use pins depending from 80 to periodically rotate gears 95 and that such projecting elements can be rigid or flexible as desired. While the greater speed of the figures in the outer slots 81 with the consequent greater lift from the actuators tends to compensate for the greater length of such slots, the fixed actuators and chance actuators may also be tilted or inclined as in Figure 3 or 5 to effect such compensation where necessary or desirable.

As an alternative method of compensating for the difference in length of circular slots such as 81, as shown in Fig. 8, I may use slots such as 100 which are of equal length in which case my actuators may be of uniform height.

In Fig. 9 I show the preferred form of my racing figure such as F, H, and J.

In Fig. 8, I show a racing figure J' having its depending arm 212 extending in a direction opposite to the nose or front 213 of the figure. As figures J' rock in slots 100 and are carried in a circular path by revolving upper member 180, certain of the figures J' lose ground to other figures due to the chance actuators such as 92. The centre of gravity of J' is in the rear of pivot 214. The figures J' are shown near the finish line of the slots 100 which line is to the left of Fig. 8.

In dotted lines is shown the position my racing figure assumes when the part 14 of 12 is contacted by an actuator, the pivot pin P having been slid along the upper member and the figure rocked backward slightly on the pivot. Also in dotted lines is shown the portion 14 of 12 in its final position after actuation when the figure H has rocked forward again due to the centre of gravity of the figure being in front of pivot pin P.

In Fig. 10, a modification is shown in the figure O pivoted on a pin P and having a depending portion 112 with a curved bottom 114. Arm 112 is integral with the figure O but may be of small cross section and comparatively light in weight. In this case I include weights of lead or other material in the nose W of the figure so that the centre of gravity is in front of the pivot and the figure tends to rotate counter-clockwise.

I may use any convenient means for increasing or decreasing the counter-clockwise moment of force around the pivot of my racing figure and thus change the amount of movement of the figure when contacted by an actuator. For

example, in Fig. 10, I show an adjustable weight 220 on the tail T of the figure O to permit such changes.

In certain modifications of my invention particularly when constructed for full size riders, I may provide stops such as 115 and 116 simulating the legs of the animal and may attach at the ends thereof a resilient member such as coil springs 117 and 118 to prevent the throwing 10 of the rider and to quickly return the figure to its normal position after actuation.

Figs. 11 and 13 show the preferred form of my chance actuator C illustrating the cut out portions 35, 36, 37, 38, in the cylinder 32 and 15 the manner in which it is carried in bearings 34 and may be revolved by a wheel such as 39.

A modified form of chance actuator K is shown in Figs. 12 and 14 in which a cylinder 120 carried on a shaft 123, in bearings 124, and revolved in any convenient manner, may have a strip of material 125 such as rubber spiraled around the surface and fixed at each end 126 and 127 to the cylinder.

It is apparent that my chance actuators C 25 or K may be so mounted as to either hold back certain of the figures or to give certain figures an additional actuation.

If desired, additional chance elements may be added to my device such as the manually operated horizontal slotted disc L, shown in dotted 30 lines in Fig. 4, as rotatably mounted at 210 proximate the end 53 of tracks 51 and adapted to normally permit only one figure H to enter a slot such as 211 in the disc and progress to the end of its slot.

Disc L may be rotated about post 210 by manual or power means and the peripheral opening of each slot 211 is just wide enough to accommodate, at most, the depending arms of 40 two adjacent racing figures. In no position of rest, therefore, can the edge of disc L stop all the racing figures and in most positions of rest it will permit only one figure to advance along its slot.

I may provide a plurality of slots 220 in disc 45 L, in addition to slots 211, each of which may be of different lengths in order to bar the further advance of the racing figures at different distances from the end of their respective slots.

I claim:

50. 1. In a figure racing apparatus: an upper member having a row of elongated track slots; a lower member having at least one immovably mounted, regularly surfaced actuator and at least one irregularly surfaced, revolvably mounted, chance actuator spaced thereon beneath and transverse to said slots, the irregular surface of each chance actuator being mounted to revolve around an axis substantially transverse to the direction of said slots; means for imparting motion to one of said members relative to the other, and racing figures, rockably pivoted on said upper member, each having an arm depending through, and extending substantially below, a slot and adapted to be impelled along said slots with a rocking motion by contact of said arm with the regular and irregular surfaces presented thereto by said actuators.

2. In a figure racing apparatus: an upper member having a row of elongated track slots; a lower member having at least one immovably mounted, regularly surfaced actuator and at least one irregularly surfaced, revolvably mounted chance actuator spaced thereon beneath and transverse to said slots, the irregular surface of

each chance actuator being mounted to revolve around an axis substantially transverse to the direction of said slots; means for imparting motion to one of said members relative to the other, and racing figures rockably pivoted on said upper member, each having an arm depending through and extending substantially below, a slot and adapted to be impelled along said slots with a rocking motion by contact of said arm with the regular and irregular surfaces presented thereto by said actuators, each racing figure having a centre of gravity spaced below its slot and pivot and toward the front of the figures.

3. In a figure racing apparatus: an upper member having a row of elongated track slots; a lower member having at least one immovably mounted, regularly surfaced actuator and at least one irregularly surfaced, revolvably mounted chance actuator spaced thereon beneath and transverse to said slots, the irregular surface of each chance actuator being mounted to revolve around an axis substantially transverse to the direction of said slots; means for imparting motion to one of said members relative to the other, and racing figures rockably pivoted on said upper member, each having an arm depending through and extending substantially below a slot and adapted to be impelled along said slots with a rocking motion by contact of said arm with the regular and irregular surfaces presented thereto by said actuators, each fixed actuator being identical and each chance actuator being revolvble by the moving member to contact each arm with a constantly varying actuation.

4. In an amusement device having an upper member provided with a row of elongated figure-guiding tracks, a racing figure rockably mounted in each track and having an arm depending substantially below said track, a lower member and means for moving one member relative to the other in a closed path, at least some of said path being in a plane parallel to the plane of said other member, the combination of at least one irregularly surfaced, revolvably mounted chance actuator on said lower member and under said tracks, each chance actuator being adapted to rock each figure and to move each figure in its track in unequal amounts, by the rotation of its irregular surface with each circuit of the path of said lower member.

5. In an amusement device having an upper member provided with a row of elongated figure-guiding tracks, a racing figure rockably mounted in each track and having an arm depending substantially below said track in a position to be contacted by actuators, a lower member and means for imparting horizontal movement to one member relative to and parallel to the other, the combination of a plurality of actuators spaced along said lower member under said tracks, at least one of said actuators being fixed and adapted to rock and advance all of said figures equally and at least one of said actuators being rotatable on a fixed axis transverse to the direction of said tracks, and having an irregular surface adapted to rock and advance all of said figures in unequal amounts by the operation of chance.

6. In a figure racing apparatus, an upper member having a row of elongated track slots; a lower member having a plurality of regularly surfaced actuators and at least one irregularly surfaced, rotatable, actuator spaced thereon transversely beneath said slots; means for im-

parting motion to one of said members relative to and parallel to the other; racing figures rockably and slidably mounted in said track slots each having an arm depending through and substantially below a slot which coacts with said actuators to slide each figure with a rocking motion along a track slot in the upper member, and a horizontal disc, revolvably mounted on said upper member, below the track slots and proximate the end of the path of the arms of all said figures, having cut out portions adapted to permit the arm of only one figure to reach the end of its track slot.

7. In a figure racing apparatus, an upper member having a row of elongated track slots; a lower member having a plurality of regularly surfaced actuators and at least one irregularly surfaced, rotatable actuator spaced thereon transversely beneath said track slots; means for imparting motion to one of said members relative to and parallel to the other; racing figures, rockably and slidably mounted in said track slots, each having an arm depending through and substantially below a track slot which co-acts with said actuators to slide each figure with a rocking motion along a track slot in the upper member, and a chance-controlled horizontal disc, revolvably mounted under the ends of the track slots in the upper member, the peripheral edge of said disc forming a barrier for the depending arms of said racing figures and said edge having a plurality of spaced radially extending disc slots, the peripheral opening of each disc slot being just large enough to accommodate two adjacent depending arms and the length of each disc slot coinciding with the ends of said track slots, whereby, regardless of the position of rest of said disc, at least one racing figure may pass along a disc slot to the end of its track slot.

8. In a figure racing apparatus the combination of an upper member having a row of elongated track slots; a lower member; means for imparting movement to one of said members relative to the other; said movement being in a closed path, at least some of which is in a plane parallel to the plane of said other member; racing figures rockably pivoted on said upper member and each slidably in a slot therein; an irregularly surfaced, chance actuator mounted on said lower member to revolve on a fixed, substantially horizontal axis and extending beneath and transverse to all of said slots, and an arm on each racing figure depending downwardly through its slot and extending forwardly of its pivot, all of said arms being adapted to engage the revolvble, irregular surface of said chance actuator during each circuit of the path of movement of one member relative to the other member.

9. A combination as specified in claim 8 wherein in the slots are concentric with radial start and finish lines and the chance actuator is radial and gradually increases in height above the lower member as it approaches the periphery thereof.

10. A combination as specified in claim 8 wherein the revolvably mounted chance actuator is revolved by an operative connection to said moving member.

11. A combination as specified in claim 8 wherein the upper member is mounted to revolve around a central pivot carried by a stationary lower member.

12. In a figure racing apparatus having an upper member with elongated track slots, a lower member, co-extensive with said upper member, means for moving one member relative to the

other in a closed path at least some of which path is in a plane parallel to said other member and a plurality of racing figures, each rockably and slidably mounted in a slot and having a single integral arm depending downwardly through said slot to rest on said lower member, the combination of means on said lower member for repeatedly engaging the arms of said figures and rockably advancing each figure an equal amount in its slot and means on said lower member for repeatedly engaging the arms of said figures and rockably advancing each figure an unequal amount in its slot, said last named means including mechanism for continuously changing the amount of actuation imparted thereby to each figure with each circuit of the path of said moving member.

13. Apparatus as specified in claim 1 wherein the slots in said upper member are concentric with radial start and finish lines, a central pivot is provided around which one of said members revolves and the arm contacting surface of each regularly surfaced actuator is of progressively greater height above said lower member as it approaches the outer periphery thereof.

14. Apparatus as specified in claim 1 wherein the slots in said upper member are concentric

5 with concentric track slots, the lower member is mounted to rotate around a central pivot below said upper member, each racing figure is supported by a single transverse pivot pin resting on said upper member and the centre of gravity of 10 each racing figure is in front of said pivot pin.
